UNITED STATES PATENT OFFICE.

GEORGE M. WATTERS, OF MINNEAPOLIS, MINNESOTA.

VAPOR ATTACHMENT FOR EXPLOSIVE-ENGINES.

1,277,796.

Specification of Letters Patent.

Patented Sept. 3, 1918.

Application filed September 30, 1916. Serial No. 123,023.

To all whom it may concern:

Be it known that I, GEORGE M. WATTERS, a citizen of the United States, residing at Minneapolis, in the county of Hennepin and State of Minnesota, have invented certain new and useful Improvements in Vapor Attachments for Explosive-Engines; and I do hereby declare the following to be a full, clear, and exact description of the invention, such as will enable others skilled in the art to which it appertains to make and use the same.

My invention has for its object to provide an improved device for supplying water vapor with the explosive mixture to internal combustion engines; and to such ends, generally stated, the invention consists of the novel devices and combinations of devices hereinafter described and defined in the claim.

The invention is illustrated in the accompanying drawings, wherein like characters indicate like parts throughout the several views. Referring to the drawings:

25 Fig. 1 is a side elevation showing the improved vaporizer applied to an explosive engine;

Fig. 2 is a vertical section of the water trap of the vaporizer;

30 Fig. 3 is a detail in section on the line 3-3 of Fig. 2; and

Fig. 4 is a side elevation of the vapor supplying valve.

In Fig. 1, the engine is indicated, as an entire, by the numeral 5, its intake manifold by the numeral 6 and the carburetor by the numeral 7. The numeral 8 indicates a radiator of the usual arrangement having an overflow pipe 9 of the customary arrangement. The instrument board of the automobile is indicated by the numeral 10. In the application of my invention, I tap the overflow pipe 9 by a vapor tube 11, and this vapor tube is extended down into the

45 air-tight shell 12 of a water trap or separator for separating the vapor from condensed water. This shell 12, which is preferably in the form of a cylindrical drum having closed heads, is preferably provided with

50 two horizontal partitions 13 formed of very fine mesh, wire screen, preferably about "80 mesh." The lower end of the vapor tube 11 terminates above the bottom of the tank but below the lower screen 13. Between the two screens 13, the vapor pipe 11 is cut away, at least in part, and the opening is covered by

a fine mesh tubular screen 14. The top of the drum 12 is connected by a vapor tube 15 to a vapor supply valve of the "petcock" type, which latter opens directly into the fuel intake manifold 6. This valve comprises a casing 16 and a tapered rotary valve 17, the latter having a depending arm 18 connected to the front end of an operating rod 19, the said rod being preferably extended through and terminating in a knob by means of which said valve may be freely moved to and from closed position.

In the bottom of the drum 12 is a drain port 21 that is normally closed by a lightly spring pressed drain valve 22 mounted in a housing 23 secured to the bottom of said drum. The tension on this valve 22 is such that it will open the water pressure from within the tank whenever the altitude of the water nearly reaches the lower end of the vapor tube 11, and in this way, automatically maintains an amount of water in the drum substantially as shown in Fig. 2.

My improved device supplies both air and water vapor but no solid water to the manifold of the engine for admixture with the hydrocarbon vapor. In the first place, only vapor will be drawn from the top of the radiator; and in the second place, any water which condenses in the pipe 11 and drum 12 will be precipitated to the bottom of the drum. Some of the vapor will escape through the tubular screen 14, and from thence will pass upward through the upper screen 13 and to the engine through the vapor tube 15, but some will pass out of the lower end of the said tube 11 and hence, if it is to reach the engine, must pass upward through both of the screens 13. These two screens positively insure condensed water from reaching the tube 15.

In practice, the device has been found efficient for the purposes had in view. The water vapor affords sufficient dampness to remove carbon and keep the spark plugs and firing chambers free of carbon. It also renders the explosive mixture more efficient and thus effects a saving in the use of gasoline or automobile fuel.

What I claim is:

A water vapor supply device for explosive engines including a closed drum having therein fine screen partitions, one above the other dividing the drum into upper, intermediate and lower chambers, a vapor tube delivering into said drum at a point be-

2
tween said screens and a vapor tube leading from said drum at a point above the upper screen, the first noted vapor tube being connected to the intermediate chamber of said drum through a fine tubular screen and having a free delivery passage leading to the bottom chamber of said drum.

In testimony whereof I affix my signature in presence of two witnesses.

GEORGE M. WATTERS.
